UNITED STATES PATENT OFFICE

JACOB GREENWALD, OF NEW YORK, N. Y., ASSIGNOR TO MENZIN SHIRT CO. INC., OF NEW YORK, N. Y., A CORPORATION

TIE-SLIP COLLAR

Application filed October 25, 1928. Serial No. 314,871.

This invention relates generally to collars and has more particular reference to a novel collar provided with a tie-slip.

The invention has for an object the provision of a device of the class mentioned, which is of simple durable construction, desirable in use and efficient in action, and which can be manufactured and sold at a reasonable cost.

10 The invention proposes the use of a collar having an outer and inner lapel consisting of outer and inner materials, and the inner material is provided with slots for forming loops providing passages for a necktie. These loops are arranged for holding a tie in a 15 sliding condition and at the same time preventing any possibility of the tie dropping down out from between the lapels of the collar. A reinforcement strip of semi-stiff 20 material is attached onto the material forming the collar in the vicinity of the slots for reinforcing the material and holding the same against wrinkling. The arrangement may be used on collars individually or on 25 collars attached on shirts.

For further comprehension of the invention, and of the objects and advantages thereof, reference will be had to the following description and accompanying drawings, and to the appended claims in which the various novel features of the invention are more particularly set forth.

In the accompanying drawing, forming a material part of this disclosure:—

25 Fig. 1 is an elevational view of the inner side of a collar having its lapels opened.

Fig. 2 is a similar view of a collar attached onto a shirt.

Fig. 3 is an enlarged fragmentary view 40 of a portion of Fig. 2.

Fig. 4 is a sectional view, taken on the line 4—4 of Fig. 3.

Fig. 5 is a view similar to Fig. 4, but disclosing a modification thereof.

45 Fig. 6 is a view similar to Fig. 3, but disclosing a modification thereof.

Fig. 7 is a vertical sectional view, taken on the line 7—7 of Fig. 6.

50 Fig. 8 is a view similar to Fig. 2, but disclosing a modification thereof.

The reference numeral 10 indicates generally a collar of any design or construction having inner material 11 and outer material 12. This collar is adapted to be folded on a central line so as to provide an outer lapel 14 and an inner lapel 15 the fold line being located between said lapels.

The inner material 11 is formed with several vertical slots 16 adjacent the outer material of the inner lapel, and these slots are so spaced so as to provide loops 17. A necktie 18 is illustrated to be engaged beneath the loops 17 for maintaining its position upon the inner lapel. A reinforcement strip 19 of semi-stiff material is secured by stitches 20 on the rear side of the inner material 11 directly behind the slot 16. The necktie, when engaged thru the slots is retained from bearing against the bottom of the slots and cause wrinkling by this semi-stiff material.

In Fig. 2 a shirt 21 has been illustrated with the collar 10 attached. This shirt may be of any design and construction and made from any material. A tie 18 is shown engaged in loops 17 as previously described.

In the modified form of the device illustrated in Fig. 5, the semi-stiff material 19 is secured by stitches 20^a onto the outer material 12 directly adjacent the slots 16. The operation of this form of the device is similar in all respects to the previous described form.

In Figs. 6 and 7, a loop 22 has been shown secured at its top and bottom ends as at 23 and 24 onto the inner lapel of the collar, and on the front side thereof. A necktie may be engaged beneath this loop for the purposes previously described.

In the modified form of the device illustrated in Fig. 8, vertical slots 16^a have been illustrated formed in the inner material 11 and extending across the inner and outer lapels. Transverse straps 25 have been secured at one of their ends as at 26 onto the inner material 11, and extend over the slots 16^a and are detachably secured at their free ends onto the material 11 by the buttons 27. A necktie 18 is shown engaged thru the slots so as to be disposed beneath the loop 17^a formed by the slots. This necktie is at 100

the upper extremities of the loops so as to be adjacent the outer lapel of the collar. When the outer lapel is turned down in the manner in which collars are worn, the necktie 18 holds this lapel against being moved upwards. Dot-dash lines 28 indicate a second position in which the necktie 18 may be placed. In this position it is disposed against the lower portion of the loops 17^a and adjacent the inner lapel of the collar. 10 When thus worn the outer lapel 14 may be turned up without interference from the necktie. Before the necktie may be moved from the first mentioned to the second position, the transverse straps 25 must be freed at their detachable ends.

20 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what 25 I claim as new, and desire to secure by United States Letters Patent is:—

30 1. A collar, comprising an outer and inner lapel of double material, and having slots formed in the inner material and extending across both the outer and inner lapels for providing a passage behind portions of the inner material so as to form loops, and transverse straps extended across the slots and detachably arranged so that a tie engaged thru said loops may be held behind one of said lapels and when desired slipped behind the other lapel without removal from said loops.

40 2. A collar, comprising an outer and inner lapel of double material, and having slots formed in the inner material and extending across both the outer and inner lapels for providing a passage behind portions of the inner material so as to form loops, and transverse straps extended across the slots and detachably arranged so that a tie engaged thru said loops may be held behind one of said lapels and when desired slipped behind the other lapel without removal from said loops, and said transverse straps being permanently attached to said loops and detachably connected with the inner material adjacent the loops.

50 In testimony whereof I have affixed my signature.

JACOB GREENWALD.
